CLAIM

I claim the ornamental design of a watch band, as shown and described.

DESCRIPTION

FIG. 1 is a perspective view of a first embodiment of a watch band.

FIG. 2 is a top view of the watch band of FIG. 1.

FIG. 3 is a bottom view of the watch band of FIG. 1.

FIG. 4 is a side view of the watch band of FIG. 1 taken from a first side.

FIG. 5 is a side view of the watch band of FIG. 1 taken from a second side that is opposite the first side.

FIG. 6 is an end view of a first half of the watch band of FIG. 1 taken from a first end that mounts to a watch.

FIG. 7 is an end view of the first half of the watch band of FIG. 1 taken from a second end that is opposite the first end and does not mount to a watch.

FIG. 8 is an end view of a second half of the watch band of FIG. 1 taken from a first end that mounts to a watch.

FIG. 9 is an end view of the second half of the watch band of FIG. 1 taken from a second end that is opposite the first end and does not mount to a watch.

FIG. 10 is a perspective top view of the watch band of FIG. 1.

FIG. 11 is a perspective bottom view of the watch band of FIG. 1.

FIG. 12 is a perspective view of a second embodiment of a watch band.

FIG. 13 is a top view of the watch band of FIG. 12.

FIG. 14 is a bottom view of the watch band of FIG. 12.

FIG. 15 is a side view of the watch band of FIG. 12 taken from a first side.

FIG. 16 is a side view of the watch band of FIG. 12 taken from a second side that is opposite the first side.

FIG. 17 is an end view of a first half of the watch band of FIG. 12 taken from a first end that mounts to a watch.

FIG. 18 is an end view of the first half of the watch band of FIG. 12 taken from a second end that is opposite the first end and does not mount to a watch.

FIG. 19 is an end view of a second half of the watch band of FIG. 12 taken from a first end that mounts to a watch.

(Continued)

FIG. 20 is an end view of the second half of the watch band of FIG. 12 taken from a second end that is opposite the first end and does not mount to a watch.

FIG. 21 is a perspective top view of the watch band of FIG. 12; and,

FIG. 22 is a perspective bottom view of the watch band of FIG. 12.

The broken lines showing a watch face in FIGS. 1 and 12 illustrate environmental structure and the broken lines shown in the remaining Figures illustrate portions of the watch band. All broken lines form no part of the claimed design. The shade lines in the Figures show contour or the flatness of a surface, and not surface ornamentation.
